CLAIM

The ornamental design for a light holder, as shown and described.

DESCRIPTION

FIG. 1 is a perspective view of a light holder according to my new design;

FIG. 2 is a top view thereof;

FIG. 3 is a bottom perspective view thereof;

FIG. 4 is a left side view thereof;

FIG. 5 is a right side view thereof;

FIG. 6 is a rear view thereof;

FIG. 7 is a front view thereof;

FIG. 8 is a perspective view thereof of a light holder in use including the light;

FIG. 9 is a top view thereof;

FIG. 10 is a bottom view thereof;

FIG. 11 is a left side view thereof;

FIG. 12 is a right side view thereof;

FIG. 13 is a rear view thereof;

FIG. 14 is a front view thereof; and,

FIG. 15 is a perspective view of the light holder including the light in use.

The broken line showing of the light holder is for the purpose of illustrating portions of the article, the broken line showing the light and backpack is for the purpose of illustrating environmental structure; all broken lines form no part of the claimed design.

1 Claim, 11 Drawing Sheets
